UNITED STATES PATENT OFFICE.

EUGENE I. BLOUNT, OF CAMBRIDGE, MASSACHUSETTS.

TICKET CANCELER AND REGISTER.

SPECIFICATION forming part of Letters Patent No. 251,022, dated December 20, 1881.

Application filed July 11, 1881. (Model.)

To all whom it may concern:

Be it known that I, EUGENE I. BLOUNT, of Cambridge, Middlesex county, State of Massachusetts, have invented an Improvement in Fare-Registers, of which the following description, in connection with the accompanying drawings, is a specification.

My invention relates to fare and ticket registers of that class in which an alarm is sounded and a registering mechanism moved when each fare is taken, and at the same time the ticket received or another registering-strip of paper or card-board is defaced or marked.

In apparatus of this kind the ticket or registering-strip has usually been marked or defaced by the action of a punch removing a portion of the said ticket, and it is possible by this method to operate upon more than one ticket at a single movement of the punch, by which a single blow upon the alarm-bell is given.

My invention has for its object to enable the ticket to be marked by the action of type, it being impossible to act upon or imprint more than one surface at each operation, and I propose to provide changeable type, in order that the date upon which a fare is received may be marked upon it, together with a characteristic mark of the company by which the fare is received, such marks being especially important in connection with transfer-checks, now largely in use, which are intended to be used for a continuous ride upon two different lines or in different cars. Such checks are marked with the date upon which they are issued upon the payment of the fare for the first portion of the ride, and upon which date only they are valid for the second portion of the ride. It is also desirable in some cities, where the tickets of several different lines are received upon each of the said lines and afterward exchanged, to impress upon the ticket the mark of the company by which it is received.

My invention consists, first, in providing, in connection with the movable lever, similar to that employed in registering-punches, a printing-die adapted to be impressed upon a ticket by the movement of the said lever in one direction, and to be provided with fresh ink by an inking-pad in the return movement of the said lever; also, in the combination, with such a printing-die, of an alarm-bell operated by the

same movement of the lever that imprints the ticket, and with registering mechanism operated by the said lever, to indicate the number of times that it has been operated.

55

The invention also consists in details of construction of the various parts, as will be hereinafter more fully described, the said construction, among other things, insuring a complete movement of the operating-lever in each direction before its effective movement in the other direction can be made.

60

Figure 1 is a side view of my improved registering apparatus, showing the printing and alarm-operating mechanism in their normal position, a part of the inclosing frame-work being removed; Fig. 2, a similar view, showing the parts in the position assumed at the end of the operation of impressing a ticket; Fig. 3, a view of the opposite side of the punch, 70 showing the registering mechanism; Fig. 4, a detail showing a portion of the said registering mechanism detached; Fig. 5, a detail of the printing-die detached, showing the opposite side to that seen in Figs. 1 and 2; and Fig. 6, 75 a modification to be referred to.

65

The working parts of the punch are inclosed in a case or frame-work, *a*, and are operated by the movement of the lever *b*, pivoted at 2 upon the said frame-work, which is of convenient form to be held in the hand of the operator. The lever *b* is provided with a projecting block, *b'*, that passes through an opening made to fit it accurately in the case *a*, and a retracting-spring, *b''*, throws the said lever outward after it has been positively pressed inward toward the case *a* by the operator, and normally retains it in the position shown in Fig. 1, the outward movement being limited by the engagement of a small projecting stud, 80 *x*, with the case *a*.

85

A bell-hammer, *e*, pivoted at 3 upon the case *a*, in position to act upon the inside of a bell, *f*, mounted on a stem, *f'*, and inclosed in a covering, *f''*, (see Fig. 6,) is provided with an arm, *e'*, having a finger, 4, which is engaged by the projection 5 of its operating-pawl *c*, pivoted at 6 upon the portion *b'* of the lever *b*, and pressed by a spring, *c'*, into engagement with the said arm *e'*, so that when the lever *b* is depressed, 95 as shown in Fig. 2, the bell-hammer *e* is turned on its pivot until just at the end of the move- 100

ment of the said lever a tripping-projection, c^2 , acts upon the pawl c to turn it on its pivot 6 and disengage the projections 4 and 5, allowing the bell-hammer e to return to the position 5 shown in Fig. 1, under the action of the spring c^2 and strike a blow upon the bell f .

The portion b' of the lever b is provided with a series of ratchet-teeth, 7, which are engaged by the retaining-pawl d as the said lever is depressed, to prevent the return movement of the said lever at any time before the bell-hammer e is released to strike the bell, as just described, when its arm e' engages the end of the pawl d , overcoming its spring d' and holding it out of engagement with the teeth 7 until the lever b has been restored to its normal position by the action of the spring b^2 , and the projection 5 of the bell-operating pawl c has passed over and engaged the projection 4 of the bell-hammer 20 arm e' .

The type-block or printing-die g is pivoted upon a stud, g' , mounted on a carriage, g^2 , slotted to receive a guide, g^3 , fixed upon the case a and pressed toward the portion b' of the 25 lever b by the spring g^4 , the backward movement of the said carriage g^2 being limited by engagement with the frame a before the lever b has completed its backward movement, as shown in Fig. 1.

30 The type-block g is provided with a hole, 8, (see Fig. 5, and dotted lines, Fig. 1,) to receive a link, h , connected with the portion b' of the lever b , so that when the said carriage g^2 has completed its backward movement under the 35 action of the spring g^4 the lever b , in its further backward movement, will, by the link h , rotate the said block g upon the stud g' to bring the type g^5 against the inking-pad g^6 , mounted in a block, g^7 , pivoted at 9, and operated upon by the spring g^8 to turn it into the 40 position shown in Fig. 2, except when a projection, 10, is engaged by the projection 12 on the block g , as shown in Fig. 1, to thus rock the said inking-pad over the type g^5 in the last 45 part of the backward movement of the lever b .

The case or main portion a of the punch is provided with a slot, 13, in which the ticket or slip to be marked is inserted; and when the lever b is depressed the link h first turns the 50 block g on the stud g' to bring the type at right angles to the slot 13, after which the portion b' engages a projection, g^8 , upon the carriage g^2 and moves the block g , with its type g^5 , directly down upon the ticket or slip inserted in 55 the notch 13. A spring, g^9 , connected with the portion b' of the lever, engages the projection g^8 of the carriage, so as to allow a slight yielding of the type-block to accommodate strips of different thicknesses.

60 The registering mechanism shown in Figs. 4 and 5 consists of a ratchet-wheel, i , pivoted at i' upon the case a , and operated by an actuating-pawl, k , pivoted at 14 on the portion b' of the lever b , the projection 15 of the said 65 pawl coming into engagement with one of the teeth of the ratchet-wheel i and rotating it for the distance of one tooth in the last part of the

movement of the said lever. A retaining-pawl, l , prevents backward rotation of the wheel i , and is so arranged as to prevent the 70 actuating-pawl k from engaging the said wheel until the last part of the movement of the lever b . A second ratchet-wheel, m , provided with a retaining-pawl, m' , is caused to rotate for the space of one tooth at each complete rotation of the wheel i by the following connecting mechanism: An arm, n , is pivoted to oscillate upon the axis of the wheel m , and is provided with a pawl, o , (see Fig. 4,) at its under side, which engages the teeth of the wheel m . The arm n is provided with a slot, 15, embracing the pivot i' of the wheel i and limiting the movement of the arm in each direction to an amount sufficient to pass the pawl o over one tooth of the wheel m , and then rotate the said wheel for the distance of one tooth. A pin, p , on the under side of the wheel i , engages shoulders n' n^2 on the under side of the arm n to give it its oscillating movement as the said wheel i rotates, as shown in Fig. 5. The pin p is shown in Fig. 4 as engaged with the shoulder n' to swing the arm n in the direction of the arrow and cause it, by its pawl o , to move the wheel m for the space of one tooth, after which the said arm n will remain stationary in the further movement of the wheel i until the pin p engages the arm n^2 and moves it back, causing the pawl o to pass over and engage a new tooth on the wheel m , now held by its retaining-pawl m' , ready to move it forward again when the pin p reaches the shoulder n' in completing the rotation of the wheel i .

In the modification shown in Fig. 6 the carriage g^2 of the type-die g is pivoted at 16 and guided at 17, thus having an oscillating instead of a sliding movement, it being operated in the same manner, as hereinbefore described, by the lever b to depress the type-block g .

I claim—

1. In a fare-registering apparatus, the main portion or case inclosing the working parts, and the actuating-lever pivoted thereon, combined with a type-block and bell-hammer and registering mechanism, all operated by the movement of the said actuating-lever, whereby 110 a mark is imprinted on one surface of a ticket or slip and an alarm given at each operation of the lever, and the number of said operations is indicated, substantially as and for the purpose described.

2. The combination, with the actuating-lever of a fare-register, of the pivoted type-block and its carriage and the inking-pad and intermediate mechanism between the said lever, type-block, and carriage, whereby in the return movement of the lever, after a fare has been registered, the type-block is removed from the ticket or slip imprinted thereby and the type are brought against the inking-pad, substantially as described.

3. In a fare-register, the main inclosing case and actuating-lever pivoted thereon, and provided with a projecting portion entering the said case, and having a series of ratchet-teeth

and a retaining-pawl to engage them in the positive movement of the said lever, combined with the bell-hammer and its actuating-pawl, connected with the said lever, and the tripping device to positively disengage it from the bell-hammer at the end of the positive movement of the lever, the said bell-hammer being adapted, when thus released by its actuating-pawl, to strike the bell and disengage the retaining-pawl from the said ratchet-teeth of the actuating-lever to permit the return movement thereof, all arranged and to operate substantially as and for the purpose described.

4. In a registering device for indicating a number of independent movements, a ratchet-wheel and actuating-pawl therefor, combined

with a second ratchet-wheel, and the pivoted arm provided with a pawl to engage the teeth of the said ratchet-wheel, and a projection upon the first ratchet-wheel to engage the said plate 20 and oscillate it in each direction, whereby the second ratchet-wheel is caused to move for the space of one tooth at each complete rotation of the first ratchet-wheel, substantially as described.

In testimony whereof I have signed my name to this specification in the presence of two subscribing witnesses.
